CHIROPRACTIC ADJUSTMENT TABLE

Thomas C. Buckley, Wichita, Kans.

Application January 13, 1947, Serial No. 721,810

1 Claim. (Cl. 311—7)

1

My invention relates to an improvement in chiropractic adjusting tables. The object of the invention is to provide a table of the kind mentioned having adjustments therein whereby a patient placed thereon may be placed in any desirable position to best receive the adjustment that is to be given.

A further object is to provide a table of the kind mentioned in which the adjustments of the table are hydraulically operated.

A still further object is to provide a table of the kind mentioned that is light in weight, simple in construction, easy and not too expensive to make and sell, one that is durable and long lived, very efficient in its work, and one that is neat in appearance. These and other objects will be more fully described as this description progresses.

Now referring to the accompanying drawings in which similar numerals of reference designate the same parts throughout the several figures of the drawings;

Fig. 1 is a side view of the table, the table being shown in its down or horizontal position.

Fig. 1A is a side view of the post support operating device of the table.

Fig. 2 is a side view of the table, the table being shown in its raised or vertical position for receiving a patient.

Fig. 2A is a sectional view through the base frame member of the table and illustrating one of the pedal controls for the table hoisting cylinders.

Fig. 3 is a bottom plan view of the table as shown in Fig. 1.

Fig. 4 is an enlarged detail side view of a typical hydraulic cylinder several of which are employed in effecting the several adjustments of the table.

Fig. 5 is a detail side view of the lower end and cap of the cylinder shown in Fig. 4, the view being taken along the line V—V in Fig. 4 and looking in the direction of the arrows.

Fig. 6 is a detail side view of an alternate mounting for the several cylinders of the table.

Fig. 7 is a cross sectional view through the cylinder shown in Fig. 6, and looking in the direction of the arrows.

Fig. 8 is a side view of an electrically operated latch employed on one of the cylinder heads by which the table top is actuated, either as a whole or in part.

Fig. 9 is a longitudinal sectional view of the bearing supporting the table top.

Fig. 10 is a cross sectional view of the bearing shown in Fig. 9, the view being taken along the

2

line X—X in Fig. 9 and looking in the direction of the arrows.

Fig. 11 is a top plan view of the spring tension control for the chest unit of the table top.

Fig. 12 is a side view of the spring tension control for the chest unit of the table top as shown in Fig. 11.

Fig. 13 is a front view of the manually operated valve unit for the control of the several cylinders employed in adjusting the table, the view being taken along the line XIII—XIII in Fig. 15 and looking in the direction of the arrows.

Fig. 14 is a rear view of the valve unit shown in Fig. 13.

Fig. 15 is an enlarged cross sectional view of the hydraulic control valves employed in operating the several adjusting cylinders of the table, the view being taken along the line XV—XV in Fig. 13 and looking in the direction of the arrows.

Fig. 16 is a foot end view of the table.

Fig. 17 is a head end view of the table.

Fig. 18 is a diagrammatical view of a pump and reservoir such as is applicable for use in providing the hydraulic pressure for operating the adjusting cylinders of the table.

Fig. 19 is a side view of the hip unit of the table top, the unit being shown in its flat position.

Fig. 20 is a side view of the hip unit of the table top, the unit being shown in its raised position.

Fig. 21 is a bottom plan view of the adjustable hip unit.

Fig. 22 is an enlarged detail sectional view of the hip unit and detachable mounting therefor, the view being taken along the line XXII—XXII in Fig. 21 and looking in the direction of the arrows.

Fig. 23 is a detail sectional view through the hip unit, the view being taken along the line XXIII—XXIII in Fig. 21 and looking in the direction of the arrows.

Fig. 24 is a detail bottom plan view of the hip unit and mounting therefor.

Fig. 25 is a side detail view of the head rest shown in its raised position.

Fig. 26 is an end view of the head rest, the head rest being shown in its lowered or flat position.

Fig. 27 is an end view of the head rest, the head rest being shown in its raised position.

Fig. 28 is a detail cross sectional view of a modified form of the cylinder caps in which solenoid 55 electric coil operated valves are employed to con-

trol the feed and discharge of the hydraulic liquid to and from the cylinders.

Fig. 29 is an enlarged detail sectional view illustrating more clearly the solenoid operation of the valves mentioned in the description of Fig. 28.

Fig. 30 is a detail fragmentary and diagrammatical side view of the table illustrating the hydraulic lines and electrical control of the valves in the hydraulic lines.

Fig. 31 is an enlarged detail view of an adjustable frame lock employed in the table, the view being as seen from the line XXXI—XXXI in Fig. 3A and looking in the direction of the arrows.

In the drawings the table is shown as having a tubular primary base frame 31 that is substantially U-shaped, the closed end of the U being at the head of the table. The base 31 is supported on suitable leg elements 32 that are attached thereto.

Each leg portion of the U-shaped base element 31 is provided with an upwardly extending curved support element 33, the ends of which are preferably welded to the leg portions of the U-shaped base 31.

Cross brace elements 34 are positioned between the upper curved portions of the supports 33, and their opposite leg of the U-shaped base 31.

A T-iron or suitable cylinder support member 35 is positioned between and rigidly attached to the legs of the U-shaped base 31 at a point just in advance of the cross braces 34.

Short aligned bearing and opposed sleeves 36 are welded to the peak of the upper curved portion of the supports 33. The ends of a tubular element 37 are journaled in the tubular sleeve elements 36.

The table top has a U-shaped secondary frame element 38, the closed end of the U also being at the head end of the table, and the legs of the U are zig-zag vertically in shaped.

At a point toward the outer ends of the legs of the secondary frame 38 the legs rest on the tubular journaled cross support element 37 and are attached, welded, thereto.

The head end of the legs of the zig-zag U-shaped secondary frame 38 are each provided with a support leg 39 which is adapted to rest on the legs of the primary frame 31, or if the primary frame 31 should be shortened in the manufacture of the table, the support leg 39 may rest on the floor.

Cross support members 40, 41, 42 and 43 are positioned between the legs of the U-shaped secondary frame substantially at the points of the bend in the zig-zag formation of the secondary frame. A longitudinally positioned support member 44 is positioned midway between the legs of the secondary frame 38 and reaches from the cross member 37 to the cross member 42 and the ends of the support 44 are welded to the cross members 37 and 42.

The table is provided with a chest and a head rest support frame which comprises a pair of vertically positioned standard plates 45 and 46, the lower ends of which are provided with tubular formations 47 in which the legs of the secondary frame 38 are slidably received. The standards 45 and 46 are spaced apart and cross members 48, 49, 50 and 51 are positioned between the standards 45 and 46 and the ends of the cross members 48, 49, 50 and 51 are welded to their respective standard 45 or 46. The cross members 48, 49, 50 and 51 are spaced apart in

horizontal parallelism with each other and lay in a plane passing through the vertical center axis of the standards 45 and 46 and are for purposes that will later be made obvious.

The ends of a curved tubular element 48a are welded to the cross frame member 48 and the curved portion of the element 48a extends toward the head end of the table and serves as a hand rest for the patient.

10 The table is provided with a U-shaped abdominal rest support frame 52, the ends of the legs, or head end of the frame 52 is pivotally mounted on the cross support member 51 and a cross member 52a is rigidly positioned between the legs of the U and in the central position thereof. The frame 52 is provided with a plate 52b that extends between the cross member 52a and the closed end of the U and is positioned midway between the legs of the U. The plate 52b is

15 provided with a centrally positioned slot 52c that is longitudinally positioned in the plate 52b, and an abdominal support cushion 53 is rigidly mounted on the foot end of the frame 52. The table is provided with a rectangular chest rest support frame 54, the head end of which is pivotally mounted on the cross member 51, and a chest support cushion 55 is rigidly mounted on the frame 54. The chest support frame 54 is

20 provided with a plate tongue element 56, one end of which is welded to the central portion of the foot end of the chest support frame 54 and extends downwardly and thence rearwardly toward the foot end of the table to a point just

25 below the foot end of the abdominal cushion support frame 52 and is positioned at a slightly downwardly degree of angle thereof. The tongue plate 56 is provided with a centrally positioned longitudinal slot 57 that is in registry with the slot 52c in the plate 52b.

30 The table is also provided with a rectangular shaped head rest support frame 58, the foot end of which is pivotally mounted on the cross member 51.

35 The head rest consists of two cushions 59 and 60 that are positioned lengthways of the table with their adjacent edges being positioned along the center longitudinal axis of the table. The cushions 59 and 60 are carried on rectangular support frames 61 and 62, the adjacent corners of which are pivotally mounted on the head rest support frame 58. The adjacent corners of the head rest frames 61 and 62 are provided with

40 meshing gear segments 63 and 64 that are rigidly mounted on the frames 61 and 62, whereby the outer edge of one of the head rest frames 61 or 62 may be raised and the opposite outside edge of its companion frame will likewise be raised or tilted as illustrated in Fig. 27.

45 The head rest support frame 58 is provided with a gear segment 65 that is rigidly attached thereto with its center axis being substantially the same as that of the gear segment 63. The under side of the head rest portion 59 is pro-

50 vided with a latch bolt element 66 that is slidably carried in bracket mountings 67 and 68, and a spring 69 is compressed between the bracket 67 and the latch bar 66 to urge engagement of the inner end of the latch bar between the teeth of the gear segment 65 to hold the head rest sections 59 and 60 in an adjusted flat or opposingly tilted positions as shown. The outer end of the latch bar 66 is provided with a finger hold

55 70 by which the latch bar 66 may be pulled from engagement with the gear segment 65 so that

the head rest portions 59 and 60 may be rocked to selected adjusted positions.

The table is also provided with a rectangular shaped leg support frame 71, the foot end of which is pivotally mounted on slide elements 72 and 73 that are slidably mounted on the frame legs 38. A leg support cushion 74 is rigidly attached to the foot end of the leg support frame 71. The table is also provided with a hip support cushion 75 that is positioned at the head end of the leg support cushion and is attached thereto by a combination hinge and demountable device therefor which comprises a pair of curved leg elements 76 and 77 one end of which is provided with hinge elements 78 and 79 which are attached to the head end of the leg support frame element 71. The other end of the legs 76 and 77 are provided with ball formations 80 and 81. The head end of the legs 76 and 77 are provided with brackets 82 and 83 that are rigidly attached to the legs 76 and 77. The table is provided with a synchronizing cross bar 84 on the ends of which is formed depending legs 85 and 86, each of which are provided with ratchet teeth 87. The upper ends of the legs 85 and 86 are pivotally mounted at 88 on the brackets 82 and 83. A spring 89 is positioned around the pivot point 88 and engages the legs 85 and 86 and the brackets 82 and 83 are so tensioned as to urge movement of the legs 85 and 86 in a forward direction so as to cause the teeth 87 to engage and rest on the edge of the frame 71 to support the hip cushion in elevated or tilted adjusted positions.

The hip support cushion 75 is provided with a pair of ball receiving sockets to receive the balls 80 and 81. Each socket is identical and are provided with a slide element 90 having a partial ball socket 91 which, in the longitudinal sliding movement of the slide 90, will slide under or from under the ball 80 or 81 to hold or release the ball 80 or 81 from the cushion 75. A spring 92 is positioned back of each slide 90 and is tensioned to urge outward movement of the slides 90 to move and retain the partial ball socket 91 under the balls 80 and 81. The slides 90 are provided with outwardly directed push rods 93, the outer ends of which project from the cushion 75. The inner ends of the push rods 93 are U-shaped and straddle the ball 80 or 81 and engage the sides of the slide 90 to actuate the sliding motion of the slide 90. The cushion 75 is also provided with a leaf spring 94 that overlies the slide 90 and balls 80 or 81 and one end thereof is adapted to spring downwardly in front of the top edge of the ball seat 91 to hold the slide 90 in a retracted position when the ball is removed therefrom.

The table is provided with a foot support platform 95 that is rigidly attached to and supported by a pair of strap iron mountings 96 and 97 which run along the outer side edges of the platform 95. The foot or outer ends of the strap iron supports are provided with downward directed end portions 96a and 97a which rest on the foot end cross member 43 of the table frame 38. The inner ends of the foot support strap members 96 and 97 are bent downwardly as indicated at 98 and are seated in slots 99 in the ends of a tubular element 100 which is positioned between the legs of the frame 38 and is eccentrically mounted on a rod 101 that passes through the tube 100 and is welded to the tube at a point diametrically across the tube from the slots 99. The ends of the rod 101 project

beyond the ends of tube 100 and are journaled in the legs of the frame 38.

The end of the lower leg of the Z-shaped element 102 is welded to the tubular element 100. 5 The upper leg of the Z-shaped element is curved and bifurcated and the bifurcations straddle a piston rod 103 and are seated in a groove in the piston rod 103 so that as the piston rod 103 moves it will rock the Z-shaped element and tube 100 and move the foot platform 95 to the dotted position shown in Fig. 1A.

The table is provided with a helical spring 95a, one end of which is attached to the cross member 43 of the frame 38 and the other end of the spring 95a is attached to the foot platform 95. The spring 95a serves to urge movement of the foot platform in the direction of the arrow A as will later be described.

Rigidly mounted on the upper end of the piston 20 rod 103 is a supplementary leg support cushion 104. The lower end of the piston rod 103 is connected to a piston that is movable in a cylinder 105 which is rigidly mounted on the cross frame member 42 of the frame work 38.

25 Rigidly attached to the bottom and at opposite sides of the cushion 104 is one end of a pair of downwardly projecting guide rods 105a and 105b. The rods 105a and 105b slidably pass through holes in the cross frame member 42, 30 and the bottom ends of the rods 105a and 105b have a head thereon to prevent the rods 105a and 105b from slipping entirely from the cross frame member 42. The rods 105a and 105b are provided with compression springs 105c and 105d 35 that are positioned around the rods 105a and 105b and are under compression between the heads of the rods 105a and 105b and the cross frame member 42. The springs 105c and 105d serve to retract the piston and piston rod 103 in the cylinder 105 as will later be described.

The table is provided with a second cylinder 40 106 that is horizontally positioned and one end of the cylinder 106 is pivotally mounted at 107 on the central portion of the frame member 44. The cylinder 106 is provided with a piston and a piston rod 108, the outer end of which is pivotally connected to the head end cross member of the frame 71 so that as the piston rod 108 is extended from or retracted into its cylinder 106 the frame 71 and cushions 74 and 75 thereon will be adjustably moved lengthwise of the frame 38. The other end of the cylinder 106 is provided with a cap element 109 that is rigidly mounted thereon and through which the piston rod 108 is slidably operable. The cap 109 is provided with an F-shaped bracket 110 that is rigidly attached thereto.

45 The table is also provided with a pair of helical springs 106a and 106b that are positioned, one on either side of the table and their corresponding ends are attached, one to the cross frame member 42 and the other ends are connected to the rectangular frame 71 and are so tensioned as to move the frame 71 toward the foot of the machine.

The table is provided with a third cylinder 50 111, the lower end of which is pivotally mounted at 112 on the cross frame member 35. The cylinder 111 is provided with a long tube-like piston 113, the lower end of which is closed and the upper end of which receives the central leg of the F-shaped bracket 110, and a pivotal pin 114 passes through the adjacent or associated ends of the piston 113 and the central leg of the F-shaped bracket 110.

The end leg of the F-shaped bracket 110 is provided with a latch bar 115 that slidably passes therethrough and the latch bar 115 in reality is the core of a solenoid electric coil 116 which is rigidly mounted on the cross frame 41 of the table. The solenoid coil 116 serves to operate the latch bar 115 to engage it with the end leg of the F-shaped bracket 110.

The solenoid coil 116 has two electric lead wires B5 which is the same as, or connects to the wire B5 in Fig. 2A, the other wire 116a of the solenoid coil 116 is one of the feed wires for the coil 116, the wire B4, of Fig. 2A, is the other feed wire for the coil 116. The rear of the solenoid coil 116 is provided with a spring 117 which also engages the rear end of the core or latch bar 115 and is so tensioned as to normally retract or hold the latch bar 115 from engagement with the end leg of the F-shaped bracket 110.

The table is also provided with a fourth cylinder 118 that is normally horizontally positioned and one end of the cylinder 118 is rigidly attached to the cross frame member 40. The cylinder is provided with a piston and piston rod 119, the outer end of which is rigidly attached to the frame member 48 of the slide frame 45-46-48.

A pair of helical springs 118a and 118b are positioned, one on either side of the table with their corresponding ends connected to the cross member 40 and the other corresponding ends being connected to the slideable cross member 43 so as to move the frames 45 and 46 in a direction toward the foot of the table.

The table is also provided with a fifth cylinder 120, one end of which is pivotally mounted at 121 on the cross frame 49 of the table. The cylinder 120 is provided with a piston and piston rod 122, the outer end of which is pivotally attached at 123 to a slide element 124 that is slidably attached to the plates 56 and 52b and is operable in the slots 57 and 52c in the plates 56 and 52b.

The table is provided with a lock for stationing the slide 124. The lock consists of a plate 124a having a slot 124b that is longitudinally positioned therein, and a bolt 124c is passed through the slot 124b and threaded into the guide plate 52b so that the plate 124a may slide cross ways of and on the guide plate 52b in or out of the path of travel of the slide 124 to obstruct or admit passage of the slide 124 along the slot 124b. Rigidly attached to the slide plate 124a is a rod 124d, the outer end of which slidably passes through the frame element 52, and an L-shaped hand hold 124f is formed on the outer end of the rod 124d for operating the slide plate 124a.

The cylinder 120 is provided with a U-shaped rack element 125. One leg of the U 125 is rigidly attached to the outer end of the piston rod 122, and the other leg of the U 125 is provided with a hole in which the cylinder 120 is slidably positioned. The central and outside portion of the U 125 is provided with outwardly directed ratchet teeth 126. A spring 127 is connected, one end to the lower leg of the U 125 and the other end to the cross slide frame member 49 and serves to retract the piston rod 122 into the cylinder 120.

A U-shaped element 128 straddles the cylinder 120 and the rack 125, and a ratchet plate 129 is rigidly mounted between the outer ends of the U 128 and is adapted to engage the rack teeth 126 to adjustably station the U 128 up and down the length of the rack 125. The ratchet plate 129 is provided with a handle 130 by which the ratchet plate 129 and U 128 may be moved as

above described. Another spring 131 is attached, one end to the rounded end of the U 128 and the other end of the spring 131 is attached to the cross member 51 of the slide frame 45-46-51 and serves to urge a swinging movement of the cylinder 120 toward the head end of the table.

The table is provided with a sixth cylinder 132, the lower end of which is pivotally mounted at 133 on the cross member 50 of the slide frame 45-46-50. The cylinder 132 is provided with a piston and piston rod 134, the outer end of which is pivotally connected at the point 135 on the head end cross member of the head support frame 58.

The cylinder 132 and piston rod 134 are provided with a U-shaped guide element 134a, one leg of the U being rigidly attached to the outer end of the piston rod 134, and the other end of the U is provided with a hole in which the cylinder 132 is slidably mounted. One end of a helical spring 133a is attached to the lower end of the U-shaped guide 134a and the other end of the spring 133a is attached to cross support member 50, and acts to retract the piston rod 134 when the hydraulic pressure is released from the cylinder 132.

The table is provided with two multiple valve blocks 136 and 137. The valve block 136 is rigidly mounted on the head end of the frame member 38, and the valve block 137 is rigidly mounted on the foot end of the frame member 31. Each valve block 136 and 137 is provided with a pressure feed passage 138 and a return passage 139. The valve block 136 has four pressure outlet valves 140, 141, 142 and 143, and four return valves 144, 145, 146 and 147. The valves mentioned are preferably needle valve type of valves such as illustrated in Fig. 15. The discharge and return passages 148 and 149 of the valves 140 and 144 leads to one end of a tube 150, the other end of which connects with and opens into the cylinder 132. Similarly, one end of a tube 151 joins the discharge and return passages of the valves 141 and 145 and the tube 151 leads to and opens into the cylinder 120. One end of another tube 152 connects with the discharge and intake passages of the valves 142 and 146, and the tube 152 leads to and opens into the cylinder 111. Also one end of a tube 153 joins with the discharge and intake passages of the valves 143 and 147, and the tube 153 leads to and opens into the cylinder 105.

The valve block 137 contains three sets of discharge and return valves that are constructed and connected together the same as illustrated in Fig. 15. In the valve block 137 the pressure discharge valves are numbered 154, 155 and 156, and the return valves are numbered 157, 158 and 159.

Each valve 140, 141, 142, 143, 144, 145, 146, 147, 154, 155, 156, 158, and 159 is provided with an operating foot pedal 140a, 141a, 142a, 143a, 144a, 145a, 146a, 147a, 154a, 155a, 156a, 157a, 158a and 159a respectively.

In Fig. 2A is shown the valve pedal rocker arm 155a that is pivotally mounted at 174 in a bracket 175 that is rigidly attached to the frame member 31. A push button electric switch B is rigidly attached to and supported by the frame member 31 in such a manner that in the rocking motion of the foot lever 155a, the lever 155a will engage and press the push button B1 upwardly to such a point that the contact point B2 will contact the contact point B3 to close the electric circuit of the wires B4 and B5.

One end of a tube 160 joins with the discharge and intake passages of the valves 154 and 157, and the tube 160 leads to and opens into the cylinder 118. One end of another tube 161 joins with the pressure discharge and return passages of the valves 155 and 159, and the tube 161 leads to and joins with the tube 152 which is a line between the valves 142 and 146 and the cylinder 111. One end of another pipe line 162 joins with the pressure discharge and return passages of the valves 156 and 159, and the pipe line 162 leads to and opens into the cylinder 106.

Each pressure discharge valve 140, 141, 142, 143, 154, 155 and 156 is provided with a rocker arm such as shown at 163 in Fig. 15. Each rocker arm 163 is pivotally mounted at 164 on a rocker arm support rod 165. The upper end of the rocker arm 163 is pivotally connected at 166 to the outer end of a link 167, the other end of which is pivotally connected at 168 to a needle stem 169 which slidably passes through a packing gland 170 and across the liquid pressure passage 138 to seat in a valve seat 171 between the passages 138 and 148. The bottom end of the rocker arm 163 is curved rearwardly to substantially a horizontal position, and the end thereof rests on the upper end of a standard 172 which is an integral part of a foot pedal lever 173 that is pivotally mounted at 174 on a mounting 175 that is rigidly attached to the frame element 31 of the table.

Each foot pedal lever 173 is provided with a foot pedal 182 that has a vertical shaft 183 that is integrally formed thereon and slidably passes through a hole in the foot pedal lever 173 and a set screw 184 is threaded into the end of the foot pedal lever 173 to engage the foot pedal shaft 183 to bind and hold the foot pedal in adjusted positions above the floor on which the table rests.

Similarly each return valve 144, 145, 146, 147, 157, 158 and 159 is provided with a rocker arm 176 that is pivotally mounted at 177 on a rocker arm support element 178 that is rigidly mounted on its respective valve block 136 or 137. The upper end of the rocker arm 176 rests adjacent the outer end of a needle valve stem 179 which is slidably carried in a packing gland 180, and extends across the return passage 139 and seats in a valve seat 181 that is positioned between the return passages 139 and 149.

Hydraulic pressure and a liquid reserve tank is employed for operating the cylinder of the table. This tank and pump may be separate from the table and may serve several such tables, either separately or simultaneously. The pump and tank will be as indicated in the diagram shown in Fig. 18 in which the pump is represented as being a gear pump 185 having a discharge pipe 186 that connects with the pipe line 138 which leads to and connects with all the pressure valves of the table or several tables. At 139 is shown a return line which connects with all the return valves of the table or several tables and connects with or discharges into a reserve and return tank 187. A pipe 188 connects between the tank 187 and the feed or intake of the pump 185. Connecting between the pipes 186 and 188 is a pipe line 189 in which is an adjustable spring loaded check valve 190. The adjustment of the spring pressure on the check valve 190 may be employed to adjust the amount of hydraulic pressure maintained in the pressure side of the hydraulic system for the operation of the table or tables.

All the cylinders employed in the table are hydraulic operated cylinders and two types of mountings for the cylinder are employed, one type is a pivotal mounting as illustrated in Figures 4 and 5, and the other is a rigid type of mounting illustrated in Figures 6 and 7. In Figures 4 and 5 is shown the cylinder D which corresponds with the cylinders 132, 120, 106 and 111. These cylinders have a head 199 on which is integrally formed a pair of ear-like elements 200 and 201 which fit between a second pair of ear-like elements 202 and 203 that are welded to the supporting frame element such as E, and two bolts are employed, one passing through each of the ears 200 and 202 and the other through the ear-like elements 201 and 203 to form the pivotal mounting for the cylinder D. The head 199 is provided with a tube coupling 204 to receive a tube or pipe, not shown in Figures 4 and 5, for the hydraulic feed and return. F represents the piston rod for the cylinder.

In Figures 6 and 7, the cylinder D corresponds with the cylinders 118 and 105, and is shown as having a head 199a having the tube or pipe coupling 204 to receive the feed and return hydraulic line the same as described for Figures 4 and 5. The cylinder D is provided with a sleeve 205 that is pressed thereon to make it rigid with the cylinder D, and bolts 206 and 207 are passed through the supporting elements, not shown, of the table and through the sleeve 205 and the ends of the bolts rest in indentures in the cylinder D to form a rigid mounting therefor.

The operation of the table is as follows. The foot pedal 155a is pressed downwardly and in this action the electric switch B first closes the switch B to energize the solenoid coil 116 and move the latch bar 115 into locking engagement with the F-shaped bracket 110, and as the pedal 155a advances in its rocking motion as the valve 155 is opened, the hydraulic liquid is admitted to flow through the pipe line 161 into the cylinder 111, whereupon the piston and piston rod 113 will move or be projected from the cylinder 111 and tip or raise the table top to the inclined position shown in Fig. 2.

The table having been thus inclined, the patient may stand on the platform 95 and then lean back against the cushions of the table, whereupon the foot pedal 158a may be pressed, whereupon the return valve 158 will be opened and the weight of the patient and table top will rock the table top to a horizontal position, whereby the piston and piston rod 113 will be moved into the cylinder 111 forcing the liquid in the cylinder 111 out through the pipe 161 through the return valve 158 and through the return line 139 into the reservoir 187 for future use.

While the table is in its raised position as shown in Fig. 2 and the patient is standing on the platform 95, the foot pedal 154a is pushed downwardly, whereupon the pressure valve 154 will be opened and hydraulic pressure will flow through the pipe 160 into the cylinder 118, whereupon the piston rod 119 of the cylinder 118 will be extended and move the frames 45 and 46 and the cushions thereon toward the head end of the table and to the desired place to fit the patient, whereupon the foot pedal 154a may be released and the valve 154 is closed, whereby the frames 45 and 46 are locked and held in their adjusted position.

The above adjustment having been made, the pedal 156a may be pressed downwardly, where-

upon the valve 156 will be opened and hydraulic pressure is therefore admitted into the tube 162 and the cylinder 106, whereupon the piston 108 is projected and moves the frame 71 and cushions thereon toward the head end of the table, and when the frame 71 and cushions thereon have come to the desired position the foot pedal 156a may be released and the frame 71 and cushions thereon are locked in their adjusted positions.

The above adjustments having been made, the foot pedal 143a may be pressed downwardly whereupon the valve 143 will be opened and hydraulic pressure will be admitted into the tube 153 and cylinder 105, whereupon the piston rod 103 will be projected to raise the cushion 104 to the desired height, whereupon the pedal 154a may be released and the cushion 104 will be locked in its adjusted elevated position. Simultaneously with the adjusting action just described, the piston rod 103 will raise the curved end of the Z-shaped element 102 to rock the Z-shaped element 102 and the tubular cam element 100 to move the foot platform 95 upwardly and forwardly, whereupon the sloping elements 96a and 97a will slide on the cross frame member 43 to move the platform 95 from the feet of the patient.

The above adjustments having been made, the foot pedal 142a may be pressed downwardly, whereupon the valve 142 will be opened and therefore hydraulic pressure will be admitted into the tube 152 and cylinder 111, whereupon the piston rod 113 will be projected and will tip the head end of the frame 71 and cushions thereon upwardly to the desired position, whereupon the pedal 142a may be released and the frame 71 will be locked in its desired position.

The above adjustments having been made, the foot pedal 141a may be pressed downwardly, whereupon the valve 141 will be opened and will admit hydraulic pressure into the tube 151 and the cylinder 120, whereupon the piston rod 122 will be extended and will tip the foot end of the frames 54 and 52 upwardly to a desired position, whereupon the foot pedal 141a may be released and the valve 141 will close and the frames 54 and 52 will be locked in their adjusted position.

The above adjustments having been made, the head cushion support frame 58 may be tiltably adjusted either up or down as desired in view of the fact the piston rod 134 is partially extended in its normal position. In view of this the foot pedal 140a may be pressed downwardly, whereupon the valve 140 will be opened and hydraulic pressure will be admitted into the tube 150 and cylinder 132, whereupon the piston rod 134 will be extended and will tip the head end of the head cushion support frame 58 upwardly to any desired height, whereupon the foot pedal 140a may be released and the head cushion support frame 58 will be locked in its adjusted position; or, if desired, the foot pedal 144a may be pressed downwardly whereupon the return valve 144 will be opened and the springs 133a will pull the piston rod 134 into the cylinder 132 to drop the outer or head end of the frame 58 to any desired position, whereupon the foot pedal 144a may be released and the frame 58 will be locked in its lowered position.

The above adjustments having been made, the adjustment of the head cushions may now be made. This is done by first pulling the latch 66 from engagement with the gear segment 65 whereupon the outside edges of the head support cushions may be rocked upwardly or downwardly

5 to form any degree of a V-shaped head rest as indicated in Fig. 27. The movements of the cushions 59 and 60 will always be equal due to the synchronization of the cushion movements by the meshing gear segments 63 and 64. The cushions 59 and 60 having been adjusted to the desired position, the latch 66 may be dropped into engagement with the gear segment 65 and the head support cushions are then locked in their adjusted position.

10 The hip support cushion 75 may be further adjusted in an upward rocking action by lifting upwardly on the head end of the hip support cushion 75, whereupon the cushion 75 will rock upwardly about the center axis of the hinges 78 and 79 and in this action the ratchet teeth 87 will ratchet across the edge of the cross frame member 71 and hold the cushion 75 in any elevated position.

15 There are occasions when it is desirable to remove one or the other side of the hip support cushion 75 from its mounting or supporting element 80 or 81 and turn one end or the other of the cushion 75 diagonally across the table and rest on the leg support cushion 74. This may be done by pressing the selected shaft button 93 inwardly, whereupon the ball seat slide 90 moves inwardly and from under its respective ball 80 or 81, whereupon the adjacent side 20 of the cushion 75 may be raised and disengaged from the ball 80 or 81 and swung over and rested on the leg support cushion 74. As this side of the hip support cushion 75 is raised and the ball 80 or 81 is thereby removed from the hip support cushion 75, the free end of the spring 94 will spring downwardly in front of the upper edge of the ball seat 91 and hold the ball seat slide 90 in its retracted position against the pressure of the helical spring 92. Now as the hip support cushion is swung back to its original position and remounted on the ball 80 or 81, the ball enters the hip support cushion 75 and as the cushion 75 is moved downwardly the ball 80 or 81 engages the leaf spring 94 and raises it, whereupon the leaf spring 94 disengages the ball seat slide 90 and the helical spring 92 moves the ball seat slide 90 outwardly so that the ball seat 91 is under the ball 80 or 81 and the cushion 75 is again mounted on the balls 80 and 81.

25 In giving a patient treatments while on the table there are times when it is desirable that the chest and abdominal supported cushions 53 and 55 will be yieldably supported and the foot end of the cushions 53 and 55 will give or swing downwardly under a downward pressure on the patient. The action just mentioned may be accomplished by pulling the rod 124d and latch 124a outwardly whereupon the latch 124a is moved from in front of the piston slide 124 and the slide 124 under downward pressure exerted on the cushions 53 and 55 will slide forwardly in opposition to the tension of the helical spring 131 that supports the cylinder 120 in an inclined position. The effective tension of the spring 131 on the slide 124 may be increased or decreased by moving the yoke and latch 128—129 up and down the U 125 to engage the ratchet teeth 126 at adjusted distances from the pivotal mounting 121 of the cylinder 120.

30 The foregoing table adjustments were such that a patient lying on the table is in a desired position to receive his treatment. After the treatment is finished the foot pedal 145a may be pressed downwardly, whereupon the return

valve 145 is opened, whereupon the springs 127 will retract the piston rod 122 and move the cushions 53 and 55 to their original or horizontal position. In this action the liquid in the cylinder 120 will be forced therefrom through the tube 151, return valve 145 and back to the reservoir tank 187.

Now the pedal 146a may be pressed downwardly, whereupon the return valve 146 will be opened and the weight of the cushions 74 and 75 and the frame 71 will press the piston rod 113 into the cylinder 111, whereupon the liquid in the cylinder 111 will be forced therefrom through the tube 152, return valve 146 and thence to the reservoir 187. When the cushions 74 and 75 have returned to their original or desired position the return valve pedal 146a may be released and the cushions 74 and 75 and their frame 71 will be locked in their lowered or adjusted position.

Now the return valve pedal 147a may be pressed downwardly, whereupon the return valve 147 will be opened and the springs 105c and 105d will pull the foot support cushion 104 downwardly and move the piston rod 103 into the cylinder 105, whereupon the liquid in the cylinder 105 will be forced therefrom through the tube 153 and return valve 147 and into the reservoir 187. When the cushion 104 has dropped to the desired position, the foot pedal 147a may be released and the foot support cushion 104 will be locked in its adjusted position.

Simultaneously with the action just described the cushion 104 will engage the upper curved leg of the Z-shaped element 102 and rock it downwardly to partially turn the tubular cam 100 and therefore draw the platform 95 downwardly, whereupon the inclined elements 95a and 97a will slide on the cross frame member 43 and this action takes place, the movement of the cam 100 will move the platform 95 against the patient's feet.

Now the pressure valve foot pedal 155a may be pressed downwardly, and in the fore part of this action the electric switch B will be closed, whereupon the electric solenoid coil 116 will be energized and move the core or latch bar 115 into engagement with the F-shaped member 110, and as the foot pedal 155a advances in its downward movement, the pressure valve 155 is opened and hydraulic pressure will be admitted through the tube 161 and into the cylinder 111, whereupon the piston rod 113 will be extended therefrom and will rock the zig-zag U-shaped frame 38 to its raised position as shown in Fig. 2. When the frame 38 has been raised to its desired position, the foot pedal 155a may be released and the pressure valve 155 will close and the frame 38 will then be locked in its raised position.

Now the return valve pedal 159a may be pressed downwardly, whereupon the return valve 159 will be opened, and the springs 106a and 106b will move the cushion frame 71 downwardly and therefore move the piston rod 108 into the cylinder 106, whereupon the liquid in the cylinder 106 will be forced therefrom through the tube 162 and return valve 159 and thence to the reservoir 187. When the cushion frame 71 has moved downwardly to the desired position, the foot pedal 159a may be released, whereupon the return valve 159 will be closed and the cushion frame 71 will be locked in its adjusted position.

Now the return valve foot pedal 157a may be pressed downwardly, whereupon the return valve

157 will be opened and the springs 118a and 118b will pull the slideable support frame 45—46—48 in a forward direction whereupon the piston rod 119 will be pressed into the cylinder 118 whereupon the liquid in the cylinder 118 will be forced therefrom through the tube 160 and return valve 157 and thence to the reservoir 187. When the frame 45—46—48 has moved to the desired position the foot pedal 157a may be released, whereupon the return valve 157 will close and the frame 45—46—48 will be locked in its newly adjusted position. The table is now ready for reuse and to be readjusted as above described.

In Figures 28, 29 and 30 is shown a modified 15 form of valve control which is the same for all the cylinders of the table. This form of control is electrical and the valves are operated by solenoid coils, each of which is controlled by preferably an electric push button. In Figures 28 20 and 29, C represents any one of the cylinders 105, 106, 111, 118, 120 or 132, each of which have a head 191 in which is formed a pressure hydraulic 25 passage 192 and a return passage 193, and the hydraulic pressure line 138 opens into the pressure passage 192 and connects with the pressure discharge 186; also the return line 139 opens into the return passage 193 and connects with the reservoir 187. If desired, the U-shaped tubular frame members 38 and 31 may be sealed at the 30 center and one half of the tubing of each frame may be used as the hydraulic pressure supply line and the other half may be used as the return line, and short tubing may be connected between the frame tubing and various pressure and return 35 passages 138 and 139 of the cylinder heads 191.

In the pressure passage 192 is a valve 194 that is adapted to open and close the passage 192 by the longitudinal movement thereof. The valve 194 is movable or urged to move to the closed 40 position by a spring 195 that is under compression between the valve 194 and the rear wall of the passage 192. The stem 194a slidably passes through the side of the cylinder head 191 and becomes the core of a solenoid coil 196 which is 45 rigidly mounted on the side wall of the cylinder head 191. The return valve 197 and associated parts are identical to those just described for the pressure valve, the solenoid coil for the return valve being designated at 198. Each coil 196 and 198 is operable from a respective push button in its electric circuit. The push buttons being carried preferably in groups such as indicated at X and Y as will readily be understood, and the cylinders and their piston rods will perform 50 the same as previously described for the manually operated foot pedal valve operating pedals.

Such modifications of my invention may be employed as lie within the scope of the appended claim without departing from the spirit and intention of the invention. Now having fully shown and described my invention, what I claim is:

In a chiropractic adjusting table of the kind described; said table having in combination, a primary base frame and a rockable U-shaped 65 secondary frame having substantially Z-legs that are parallel and are in registry with each other, said primary frame having vertically positioned supports stationed thereon at the foot end of the frame and being positioned between the said supports and the upper legs of the Z formations of the secondary frame being pivotally mounted on the uppermost portion of the said supports, a slide support frame, said slide support frame being slidably carried on the lower legs of the 70 Z formation of the secondary frame, said slide 75

15

frame being substantially the same height as the said Z formation, individual head, chest, abdominal, hip, leg and foot cushions, a foot platform, and a frame for each of said cushions, the foot end of the head cushion support frame and the head end of the chest and abdominal cushion support frames being pivotally mounted on the upper end of said supports on the said slide frame, the hip and leg cushion support frame being pivotally mounted at its foot end and being slidable longitudinally on the said secondary frame, and means rigidly carried by the said secondary frame for the support of the foot support cushion, said foot platform being adjustably carried by the foot end of the said secondary frame and at an angle obtuse to the general linear dimension of the secondary frame, said foot platform being adjustable toward and away from the

5

10

said foot support cushion, and means for sliding and holding the said slide frames and hip and leg cushion support in adjusted positions on the secondary frame.
